TYPEWRITING MACHINE

William F. Helmond, West Hartford, Conn., assignor to Underwood Elliott Fisher Company, New York, N. Y., a corporation of Delaware

Application December 30, 1939, Serial No. 311,761

9 Claims. (Cl. 197—74)

This invention relates to case-shifting mechanisms for typewriting machines.

In its more specific aspects, the invention claimed herein is directed to the construction and organization of means for guiding a case-shift member including preferably a type-bar segment, for movement to different case-positions.

Reference is hereby made to my prior filed application Serial No. 163,739 filed September 14, 1937, and now Patent No. 2,226,931, issued December 31, 1940, which discloses some of the inventive features herein claimed.

In typewriting machines it is extremely important to guide the case-shift member accurately and firmly within the typewriter frame so that all type impressions will be uniform as to spacing and impression. This usually requires extremely accurate manufacture of all parts that pertain to the guiding structure of the case-shiftable element; and in most cases the attention of a highly skilled mechanic is required to adjust the mechanism for satisfactory performance. Also, the frame of the machine is sometimes slightly distorted in transportation, or parts become worn after extensive usage, so that the above-mentioned fine adjustments need to be made again in the field. These conditions add to the cost of manufacture and maintenance of the machine.

Some of the major objects of the invention are:

To provide a case-shift guiding structure, the parts of which cost little to manufacture and which can be quickly and conveniently assembled by substantially unskilled labor, at extremely low cost, without the necessity of making fine adjustments; while providing for accurate and firm guidance of the case-shift body.

To provide a case-shift guiding structure which never need be adjusted for reasons of wear, or slight distortion of the frame of the case-shift guide structure.

Still other objects and advantages will be apparent from the detailed description of the invention.

The case-shift member is guided by a novel organization of devices or means having differing functions, but all cooperating to obtain a common result, namely, the accurate guidance of the case-shift member within the typewriter frame. In the embodiment of the invention shown, there is at each lateral end of the case-shift member or body an individual rolling element or ball substantially equally near the platform, each of which cooperates with a guideway

on the frame and a guideway on the case-shift body. The said balls and guideways constitute universal bearing contacts between the frame and the case-shift body and guide the body at the locations of the balls along definite linear paths. As far as these ball bearings are concerned, the case-shift body can swing fore and aft as well as laterally. Also, the comparative nearness of the lateral ends of the body to the typing line is not definitely controlled by the cooperation of the balls and the guideways. Farther from the typing line, the case-shift body is guided in a manner to restrain it only from swinging fore and aft about the balls under maintenance of some lateral freedom for said body at this location. A ball pivoted substantially parallel to the typing line has arms articulated to the case-shift body at laterally spaced points to thereby constrain the body to case-shift in unison at both of its lateral ends. The bail is articulated to the case-shift member at said laterally spaced points in such manner that a limited amount of misalignment of universal character is possible.

At least one of the above guideways is preferably in the form of a spring-leaf that is mounted to resiliently press against its associated rolling element or ball to thereby eliminate all play between the guideways and the associated rolling element at both ends of the case-shift member. It is therefore unnecessary to provide for accurate adjustment and alignment of the guideways since the rolling elements will nevertheless be resiliently held in suspension by the action of said spring-leaf.

Referring now more particularly to the drawings:

Figure 1 is a perspective view showing the case-shift mechanism of applicant's machine in normal, lower-case typing position.

Figure 2 is a plan view showing a portion of the guiding mechanism for the case-shiftable member.

Figure 3 is a side elevation of applicant's machine showing the case-shift mechanism in lower-case position, the right-hand side-wall of the machine having been omitted.

Figure 4 is a sectional front view of applicant's machine featuring the general organization of the component guiding devices for the case-shift member.

Figure 5 is a side view similar to Figure 3 but illustrating the case-shift mechanism in upper-case typing position.

Figure 6 shows an enlarged view of a lock to

normally hold the case-shift member in lower-case position against downward movement,

Figure 7 is an enlarged view of a bent guideway plate, and

Figure 8 is a detail perspective view of a wedge-plate forming part of the guide structure of the case-shift member.

In the illustrated embodiment of the invention, type-bars 10 are confined in slots 11 on a segment 12 to swing about a common, curved fulcrum wire 13 toward and away from a platen 14. The platen is rotatably mounted in a carriage frame 17, which is adapted to move on a front-rail 18 and a rear rail 19. Both rails are mounted on the framework of the machine which is generally designated by the numeral 21. The segment is secured by screws 22 to a case-shiftable member or body 23 having a cross-piece 25 and two laterally spaced legs 24. Each type-bar is operable by a spring-retumed type-key 27 provided in the keyboard of the machine. The type-keys 27 are mounted upon the forward ends of key-levers 28 which are pivoted on a common fulcrum rod 29 behind and below the segment. Upright levers 31 are pivoted on a common fulcrum rod 34 and are operable by said type-keys 27 by short links 35. Wire links 32 connect the upper ends of the levers 31 with downwardly and rearwardly extending arms 33 of associated type-bars 10. The fulcrum wire or rod 34 for said upright levers 31 is embedded in a cross-bar 36 of the framework 21 and the cross-bar 36 has slots 37 to laterally guide the levers. The type-bar operating mechanism as described is substantially disclosed in my Patent No. 2,072,878 issued March 9, 1937, and allows case-shift movement of said bars 10 relative to the levers 31 without causing pivotal displacement of the bars.

The front ends of the type-bars 10 lie normally against a curved type-bar rest 38 that is carried by laterally spaced studs 39 extending forwardly from the front-side of the case-shift member 23. Each type-bar is provided with a lower-case type 41 and an upper-case type 42, and the segment is movable to either one of two case-positions so that the desired case-types will make imprints at the typing line 43 during the actuation of the type-bars.

The case-shift member 23 is of firm structure and is guided by anti-friction bearings 45 and 46 at spaced locations equally distant from the typing line 43, along parallel lines extending substantially transverse to the typing line. Each bearing includes a rolling element in the form of a ball 47, a guideway 48 on the member 23, and a guideway 49 on the frame 21. The guideways 48 face outwardly from the member 23 and are preferably formed in leaves or plates 51 of hardened steel which are anchored to the member 23 in cantilever manner below the bearings 45, 46 by bolts 50. The upper portion of preferably only one of the leaves 51, in the drawings the right-hand one, is bent outwardly from its anchorage away from the member 23, as seen at 53 in Figures 1 and 4, to bear with tension against the associated ball 47. The left-hand plate 51 is preferably straight and in direct contact with the side of the member 23 as seen at 54, and the guideway 48 thereon is therefore definitely aligned with the side of the member 23. Both balls 47 are suspended and maintained in frictional rolling contact between both their associated guideways 48, 49 through the lateral pressure exerted by the said bent plate. All play in the anti-

friction bearings 45 and 46 is therefore eliminated without the necessity of making difficult adjustments to any one of the guideways 48 and 49. The guideways 49 on the frame are provided upon heads 55 that form part of threaded studs 56. The studs extend laterally through bosses 57 on the machine frame and the heads 55 are tightly drawn against the bosses by means of nuts 58 on the studs, see Figures 2 and 4. The heads 55 bearing the guideways 48 have flat sides 59 whereby they are rotatively located with respect to the frame 21 in recesses 60 provided on the bosses 57. Under one of the heads 55, on the drawings the left-hand one, see Figures 1, 2 and 4, there is provided a wedge plate 61 which for convenience of assembly may have an open slot 62 for placing it over the stud 56. The balls 47 are conveniently introduced between the guideways 48, 49 before the wedge plate 61 is inserted underneath the head 55. With the balls in position, the wedge is inserted to a position in which the guideways 49 will be so close together that the space 53 under the right-hand plate 51 is almost eliminated. A nut 58 is thereafter tightened to secure the head 55 with the wedge 61 underlying it. The guideways 48 have closed ends to confine the balls, their lengths just sufficient to permit unhindered case-shift movement. The upper ends of the plates or leaves 51 are confined between edges 64 to accurately locate and hold them located with respect to the case-shift member 23.

Each of the legs 24 of the case-shift member 23 supports a roller 65 at a distance farther from the typing line than the said bearings 45, 46 are located. These rollers are pivotally mounted on the legs 24 by screws 66 and are guided between front guide-faces 67 and rear-guide faces 68 provided respectively on a bracket 69 secured to a cross-bar 70 in the machine frame and the cross-bar 70 itself. These guide-faces 67 and 68 lie in parallel planes and the position of the rollers 65 and therefore also the position of the case-shift member is not laterally restricted thereby.

Synchronized movement of the case-shift member 23 at its ends is assured by the provision of a bail 72 having arms 73 articulated to the member 23 at laterally spaced points. The arms 73 of the bail are connected by a bail-shaft 74 which is pivoted upon pivot studs 75 at each lateral end thereof in the machine frame. See Figure 1. The bail arms 73 extend forwardly from the shaft 74 and have laterally extending pins 76 upon which shoes 77 are pivotally carried. Each shoe 77 fits slidably between a pair of parallel guide faces 78 on the said member 23 that face each other substantially in the direction of the case-shift movement. Ample lateral space is provided between the shoes 77 and the member 23 to allow the positioning of the case-shift member intermediate the bearings 45, 46 without lateral interference. The forward ends of the arms 73 act through said shoes 77, solely to compel both ends of the case-shift member 23 to move in unison. The shoes 77 provide a wide and accurate wearing surface to articulate the bail-arms 73 to the member 23.

The component parts providing for the guidance of the case-shift member need only be of reasonably accurate manufacture and will give perfect performance if so made. No difficult adjustments are required to faultlessly assemble the case-shift member upon the frame. It should be noted that the position of the case-shift member 23 at each of its ends conforms readily with the

position of the bail 72. This is so even if the bail 72 is inaccurately pivoted in the machine or of inaccurate manufacture. In other words, the bearings 45, 46, the roller 65, and the guide-ways 67 and 68 are not controlling as far as keeping the member 23 in horizontal alignment with the platen is concerned. The bail in no event interferes with the free movement of the member 23 nor do the bearings 45, 46 interfere with the free movement of the bail.

The case-shift member normally occupies the position seen in Figures 1, 3 and 4 and is locked or propped in this position by two laterally spaced upright arms 80, each one of which underlies a roller 81. Each roller 81 is preferably pivotally supported by one of the bolts 50 which serve to support the plates 51 on the case-shift member 23. The bolts have eccentric pins upon which the rollers are pivoted and the position of each roller 81 is adjustable toward or away from the arm 80 underlying it, by turning its associated bolt 50 prior to tightening the nut on the bolt. If properly adjusted, the rollers 81 will directly overlie a dwell 82 on the arms 80 when the case-shift member 23 is in the normal case position seen in Figures 1 and 4.

Overlying the plates 51 and secured by the bolts 50 are brackets 83, one at each member end. The brackets 83 have each a horizontally bent ear, to each of which a spring 84 is attached. The springs 84 are anchored in holes provided in washers that underlie the nuts 56. The springs 84 are sufficiently strong to normally urge the member 23 upwardly to lower-case position. Both brackets 83 carry at their upper ends adjustable upper-case stops 86 and lower-case stops 87 which are engageable with the bosses 57. The lower-case stops 87 are so adjusted that the case-shift member 23 is normally rigidly confined against movement by the lower-case stops 87 and the dwells 82 of the arms 80. Both arms 80 are secured to a transverse rock-shaft 88 which is pivoted at its ends in the brackets 69. A spring 85 on the shaft 88 urges both arms to the normal position seen in Figure 1, in which position stop-ears 89 on the arms 80 abut the top edge of the cross-bar 70. A case-shift key lever 91 shown in Figures 1, 3 and 5, carries at its forward end a case-shift key 90 and is pivoted at the rear upon the fulcrum rod 29. A spring 97, near the pivot 29, urges the shift-key lever to normal position seen in Figure 3. A finger 92 on the lever 91 overlies a pin 93 on an arm 94 that is pivoted on a frame-part of the machine. The arm 94 has at its rear end a vertical link connection 95 with a leftwardly extending arm 96 of a lever 98 that is pivoted at 99 to a bracket 100 secured by screws 103 to the left leg 24 of the case-shift member 23. The lever 98 has an arm 101 which extends rightwardly from the pivot 99 and carries a roller 102 which lies behind a cam face 104 provided on one of the arms 80. The left arm 96 of the lever 98 normally rests against a stop-lug 107 provided on the bracket 100 and the lever is free to rock counterclockwise about its pivot 99 until its arm 96 engages another stop-lug 108. As will be readily understood from the drawings, an initial downward depression of the case-shift key 90 will through the parts 91 to 96 first rock the lever 98 from its position against the stop 107 to a position against the stop 108. During this movement of the lever 98, the member 23 remains stationary while arms 80 are rocked forwardly through the action of the roller 102 upon the cam 104. At the time the lever 98 abuts the stop ear

108, the arms 80 are in a forward position indicated at 110 in Figure 6, and cease to lock the case-shift member 23 against movement. An extended motion of the case-shift key 90 will thereafter pull the case-shift member 23 to lower-case position. It will be understood that the lever 98 during this motion moves bodily with the member 23 because it is engaging the stop-ear 108. During the downward shift of the member 23, the arms 80 are idly rocked farther forward to the position indicated at 112, Figure 6, by the engagement of the rollers 81 with the cam-faces 111 on the arms. Upon release of the case-shift key 90, the member 23 is lifted by the springs 84, and also through the action of said cam-faces 111 on the rollers 81 to normal case-position.

In Figure 4, the case-shift member 23 is shown as having two spaced rearward arms 113. A rocker bail 114 is pivoted between the arms 113, and a universal bar 115, individually operable by all the type-bars 10, is pivotally connected to the upper end of the rocker 114 and 116, see Figure 3. The front end of the universal bar 115 is slidably mounted in the segment in a manner not shown but well known in the art. A substantially horizontal link 117, articulated to the universal bar at a point coaxial with the point 116, extends rearwardly and has a pivotal connection at 118 with a carriage-feed escapement 119. The link 117 provides a universal connection between the escapement 119 and the universal bar which is operative in either case-position of the member 23. The link-connections are loose so that the case-shift member and its supported parts, specifically also the universal bar, need not be in accurate lateral alignment with the carriage-feed escapement. The carriage-feed escapement 119 controls the letter-feed movement of the carriage 17 through the medium of an escapement wheel 120, a pinion 121 on said escapement wheel and a rack 122 on the carriage 17.

Having thus described my invention, I claim:

1. In a typewriting machine having a case-shiftable body; means for guiding said body for case shifts, comprising upper guide-means at which said body is confined against horizontal lateral displacement, lower guide-means cooperating with the upper guide-means to constrain said body in respect to fore-and-aft displacement, said upper guide-means having swivel bearing contacts with said body allowing the latter to swing laterally about said contacts, and said body having the capacity of some lateral freedom at the lower guide-means, and means pivotally anchored in a support in the machine having connections with said body at laterally spaced locations to compel both of its lateral ends to case-shift in unison.

2. In a typewriting machine having a case-shiftable body; means for guiding said body for case shifts, comprising upper guide-means at which said body is confined against horizontal lateral displacement, lower guide-means cooperating with the upper guide-means to constrain said body in respect to fore-and-aft displacement, said upper guide-means having swivel bearing contacts with said body allowing the latter to swing laterally about said contacts, and said body having the capacity of some lateral freedom with respect to the lower guide-means, and two laterally spaced members connected for substantially up-and-down movement in unison in a support in the machine and connected at laterally spaced locations to said body so that said body

is not constrained laterally by said members or vice versa.

3. In a typewriting machine having a body case-shiftable within a frame; means for guiding said body for case shifts, comprising upper guide-means comprising individual balls cooperating at laterally spaced locations with guideways on the frame and said body and thereby confining the latter at these locations against horizontal lateral displacement, lower guide-means cooperating with said upper guide-means to constrain the said body in respect to fore-and-aft displacement, said individual balls constituting universal bearing contacts between the frame and the body and the body having the capacity of some lateral freedom at the lower guide-means, wherefore the body is liable to tilt laterally, and means to constrain said body to case shift at both of its ends in substantial unison, including provision rendering the fore-and-aft and lateral position of said body to some extent independent of said last means.

4. In a typewriting machine having, a frame, a case-shiftable body carrying an arcuate array of type-bars, levers on said frame and means to operate said type-bars by said levers in different case-positions of the body; means for moving and guiding said body for case-shifts, including, laterally spaced upper guide-means, laterally spaced lower guide means, one of said spaced guide-means comprising individual balls cooperating at two spaced locations with guideways provided oppositely on the frame and said body, thereby confining the latter at these locations against horizontal lateral displacement while giving the body the capacity to swivel about either of these locations, the other of said guide-means being constructed to allow some lateral freedom for said case-shiftable body, both said guide-means conjointly providing for fore-and-aft restraint of said body, and means to compel uniform up-and-down case-shift movements of the said body at both of its lateral ends, said means being loosely articulated with said body to enable it to vary its position to a limited extent in relation to said body.

5. In a typewriting machine having a case-shiftable body; means for guiding said body for case shifts, comprising upper guide-means at which said body is confined against horizontal lateral displacement, lower guide-means cooperating with the upper guide-means to constrain said body in respect to fore-and-aft displacement, said upper guide-means having swivel bearing contacts with said body allowing the latter to swing laterally about said contacts, and said body having the capacity of some lateral freedom at the lower guide-means, a pivoted bail having laterally spaced arms, and means connecting said arms to said body to restrain it from swinging laterally and to compel it to move in unison at both of its lateral ends, said connecting means providing for some relative fore-and-aft and lateral freedom of position for the bail and said body.

6. In a typewriting machine having a frame and a case-shiftable body; means for moving and guiding the said body for case-shifts, including, upper-guide-means comprising two laterally

spaced guideways on the frame facing laterally in opposite directions, an individual guideway on said body laterally adjacent to each one of the said guideways on the frame, an individual ball between each adjacent pair of guideways and means for mounting and resiliently pressing at least one of the guideways laterally against its associated ball, wherefore resilient lateral pressure maintains both balls in rolling contact between the associated guideways and the body is confined against horizontal lateral displacement, lower guide-means cooperating with the upper guide-means to constrain said body in respect to fore-and-aft displacement, the said body having the capacity of some lateral freedom at the lower guide-means, and means articulated at spaced locations to the said body providing for case-shifting movement of both lateral ends of said body in unison.

20 7. In a typewriting machine, two relatively case-shiftable bodies, a member of resilient material springing in cantilever manner from a support on one of said bodies, two guide-ways, one being provided on said resilient member and the other one on the other one of said bodies, a rolling element between said guide-ways, said resilient member, by springing from its support, being effective to hold said rolling element frictionally engaged with both said guide-ways, and means cooperative between said one of said bodies and said member to give guiding support to the cantilever-end of said member.

35 8. In a typewriting machine, a frame having widely spaced parallel guide-ways facing in opposite directions, a type-element-supporting case-shiftable body, comprising a cross-member having a leg at least at one end, a leaf of resilient material supported in substantially parallel relation on said leg and having a cantilever-end provided with a guide-way facing one of said spaced guide-ways and springing toward it, another guide-way on the other end of said cross-member facing the other one of said spaced guide-ways, a rolling element between each pair of facing guide-ways, 40 said cantilever-end, by springing toward one of the said spaced guide-ways, being instrumental to hold the rolling elements in tight rolling contact between the pairs of facing guide-ways, and guiding means associated with said leg to guide said body at a location distant from the said rolling elements.

50 9. In a typewriting machine, a frame having widely spaced parallel guide-ways facing in opposite directions, a type-element-supporting case-shiftable body comprising a cross-member having a leg at each end, a leaf on each one of said legs, supported in substantially parallel relation thereto, each leaf having a guide-way facing one of said spaced guide-ways, a rolling element between each pair of facing guide-ways, at least 55 one of said leaves having a cantilever-end whereon its guide-way is provided, the cantilever-end springing from said leg in a manner to hold said rolling elements in tight rolling contact between the pairs of facing guide-ways, and guiding means associated with said legs to guide said body at locations distant from said rolling elements.

WILLIAM F. HELMOND.
